UNITED STATES PATENT OFFICE.

JAMES C. LEDBETTER, OF NEW YORK, N. Y., ASSIGNOR TO UNITED STATES HOFFMAN MACHINERY CORPORATION, OF NEW YORK, N. Y., A CORPORATION OF DELAWARE.

PRESSING MACHINE.

Application filed May 17, 1923. Serial No. 639,595.

This invention pertains to improvements in presses designed more particularly for use in pressing garments, laundry work and the like.

5 The main object of the invention is to produce a press wherein a high degree of pressure may be effected between the pressing elements and this by the utilization of power means which is automatically brought into 10 operation after the pressing elements have been manually brought to their closed position.

With this and other objects and advantages, which will hereinafter appear, reference will be made to the annexed drawings 15 wherein:

Figure 1 is a vertical sectional elevation of the press embodying my invention with the pressing elements in their open or separated position; and

Figure 2, a detail sectional elevation showing the relation of certain of the parts which obtains when the press is exerting final heavy pressure upon the garment or article at such 25 time positioned between the pressing elements.

In the drawings, 1 denotes the main frame of the machine upon which is supported a buck or fixed pressing element 2. Fulcrumed upon an upward extension 3 of the frame or 30 between two such elements, as is common in practice, is a press lever 4 carrying at its forward end a press head 5 and a handle 6 by which the press head may be drawn downwardly during the initial closing of the press. The lever at its rear portion is provided with a counterweight 7, so that the lever may be 35 readily moved through a downward movement upon the handle 6. Fulcrumed upon a fixed bearing or shaft 8, located at the rear of the frame is a bell-crank lever, the vertical arm 9 whereof is relatively long while the horizontally disposed arm 10 is relatively short. Fulcrumed at 11 at the inner end of 40 the arm 10 is a link 12 of a toggle, the other link 13 of the toggle being pivotally connected by a through pin or bearing member 14 to the press lever 4. The link 13 embodies a yielding take-up or pressure element 15 as 45 well understood in the art. Straightening of the toggle, of course, rocks the lever and brings the head 5 into pressing relation to the buck and to effect this, I employ a second 50

toggle comprising links 16 and 17 to the latter of which there is pivotally connected a 55 draw-bar or link 18, the lower end of which is pivotally attached to a treadle lever 19. Depression of the lever 19 to the position shown in Figure 2 straightens the toggle 16, 17 and causes the links 12 and 13 to come 60 into alignment and through the rocking of the lever 4, close the head upon the buck with an initial degree of pressure. Such degree of pressure may be regulated within a limited extent by an adjustment of the take-up 15 65 and an adjustment of the length of the draw link 18. A stop 20 limits the downward movement of the treadle, the arrangement being such, however, that the toggle 16, 17 will assume its straightened position and hold 70 the head in its closed relation.

To obtain the high degree of pressure which is essential in certain work, as for instance, edge pressing, I provide means whereby the bell-crank may be rocked and an upward 75 thrust imparted to the then straightened pressure toggle 12, 13. Secured upon the frame of the machine is a cylinder 21 in which is mounted a piston 22, the piston rod 23 whereof extends rearwardly and is connected by a 80 link 24 to the upper end of the long arm 9 of the bell-crank. From this it will be seen that when the piston is moved outwardly or toward the left, the bell-crank will be rocked and direct upward pressure exerted upon the 85 pressure toggle and through the lever 4 to the head 5. To effect the admission of steam, which usually supplies the heating chamber in the head or other portion of the press, or to the spray surface, such as is commonly 90 employed in the presses of today, I provide a pipe 25, extending from the main supply line 26, which latter is connected to the boiler. Mounted in the line 25 is a valve 27, which is normally drawn to its seat by a spring 28, 95 mounted upon the valve stem, which latter is extended downwardly and passes through a guide 29. To the lower end of the stem there is pivotally connected a link 30 which in turn is connected to the inner end of a lever 31 fulcrumed at 32, upon a fixed portion of the frame.

The treadle lever 19 carries an adjustable contact screw 33, which when the treadle lever 19 is carried to its lowermost position contacts 105 the outer end of the lever 31, thereby rocking

the same and opening the valve 27 against the action of the spring 28, thus admitting steam or other fluid under pressure through the pipe 25 into the right hand end of the 5 cylinder 21 thereby causing the piston 22 to travel outwardly and as above noted, effect the rocking of the bell-crank lever and the exertion of heavy pressure between the pressing elements.

10 Fulcrumed upon a fixed bar 34 at a point below the pedal lever is a kick-off pedal or lever 35, said lever being normally held in its inactive position or that shown in both figures by a spring 36 connected to the lever and to 15 a stop 37 fixed to the frame 1 of the machine. Said lever has connected to it a link or rod 38, said rod extending upwardly and being pivotally connected to the handle or lever 39 of an exhaust valve 40, which communicates 20 with the right hand end of the cylinder. The kick-off pedal 35 also carries at its inner end a set screw 41 adapted to coact with a pad or abutment 42, formed on the lower face of the treadle lever 19. Thus, it will be seen that 25 when the outer end of the treadle lever 35 is depressed, the link 38 will be moved upwardly, opening the exhaust valve 40 and allowing the steam to exhaust from the cylinder 21, which exhaust may be led to any desired point through suitable piping, not shown. The exhaust of the steam from the cylinder permits the piston to move to the right and likewise allows the bell-crank to rock so that its lower arm 10 swings downwardly, relieving the press of the high pressure.

Continued upward movement of the inner end of the kick-off pedal 35 brings the set screw 41 into contact with the pad 42, thereby 40 forcing treadle lever 19 upwardly, breaking the toggle 16, 17 and allowing the press head to swing open. Such opening movement is assisted by the use of a spring 43, interposed 45 between the thrust toggle and a fixed portion of the machine.

From the foregoing it will be seen that the structure is relatively simple and that the press is economical in the use of steam because of the high leverage obtained through the use 50 of the bell-crank lever and connecting the piston rod to the long end of said lever.

What I claim is:

1. In a garment press the combination of 55 cooperating pressing elements; a lever by which one of said elements is carried; a toggle serving to rock the lever and to bring the pressing elements into pressing relation; a treadle lever; means interposed between said lever and the toggle for straightening the latter when the treadle lever is depressed; fluid actuated means acting upon the toggle to apply endwise movement thereto when the same is straightened; a source of fluid pressure; a valve normally cutting off the supply of pressure to the fluid actuated means; means inter-

posed between the treadle lever and said valve for opening the valve when the toggle has been brought to its straightened position upon a depression of the treadle lever; and means acting to permit an exhaustion of the 70 fluid pressure from the cylinder when the treadle lever is released.

2. In a garment press the combination of 75 cooperating pressing elements; a lever by which one of said elements is carried; a toggle serving when straightened to rock the lever and bring the pressing elements into pressing relation; a second toggle, said second toggle being connected at one end to a fixed portion of the structure and at its opposite end to the toggle first mentioned; a treadle lever; a link interposed between said lever and the second named toggle and serving when the treadle is depressed to straighten the second named toggle and through such 80 straightening action to straighten the first named toggle; a cylinder; a piston mounted within said cylinder; connections intermediate said piston and the first mentioned toggle and serving as the piston is moved in one direction to exert an endwise thrust upon the first named toggle; a source of fluid pressure; a normally closed valve having a valve stem, located between said source and an inlet to the cylinder; a lever connected at one end to the valve stem, said lever standing in the path of movement of the treadle lever and serving as the treadle lever contacts the same, as it is moved to straighten the second named toggle, to open the valve and admit fluid under pressure to the cylinder; and means under the control of the operator for throwing the treadle lever upwardly and thereby releasing the parts and simultaneously opening an exhaust passage leading from the cylinder.

3. In a garment press the combination of 105 cooperating pressing elements; a lever by which one of said elements is carried; a toggle serving when straightened to rock the 110 lever and bring the pressing elements into pressing relation; a second toggle, said second toggle being connected at one end to a fixed portion of the structure and at its opposite end to the toggle first mentioned; a treadle lever; a link interposed between said lever and the second named toggle and serving when the treadle is depressed to straighten the second named toggle and through such 120 straightening action to straighten the first named toggle; a cylinder; a piston mounted within said cylinder; connections intermediate said piston and the first mentioned toggle and serving as the piston is moved in one direction to exert an endwise thrust upon the 125 first named toggle; a source of fluid pressure; a normally closed valve, having a valve stem, located between said source and an inlet to the cylinder; a lever connected at one end to the valve stem, said lever standing in the path 130

of movement of the treadle lever and serving as the treadle lever contacts the same, as it is moved to straighten the second named toggle, to open the valve and admit fluid under pressure to the cylinder; an exhaust valve in communication with the cylinder; a kick-off pedal for the treadle lever; and connec-

tions between said kick-off pedal and the exhaust valve to open the valve just prior to the release of the treadle lever.

10

In testimony whereof I have signed my name to this specification.

JAMES C. LEDBETTER.
